UNITED STATES PATENT OFFICE.

THEODORE HUBERT, OF NEW YORK, N. Y., ASSIGNOR TO CHARLES F. SPLITDORF, OF NEW YORK, N. Y.

ELECTRICAL IGNITION APPARATUS.

No. 926,654.

Specification of Letters Patent. Patented June 29, 1909.

Application filed January 25, 1908. Serial No. 412,537.

To all whom it may concern:

Be it known that I, THEODORE HUBERT, a citizen of the United States, and resident of New York city, borough of Manhattan, in the county of New York and State of New York, have invented certain new and useful Improvements in Electrical Ignition Apparatus, of which the following is a specification.

10 The object of my invention is to provide improved means for producing sparks in the cylinders of explosion engines, and particularly to cause accurate firing in the cylinders at the required time, and my invention is especially applicable for use in multiple cylinder gas engines of high speed.

Attempts have been made to utilize an induction coil for each engine cylinder in connection with a single vibrator for all the 20 coils for causing the make and break of the circuit for each coil. In such ignition systems, as known to me, the difficulty experienced is that they introduce inductance, and destroy or retard the desired effect, 25 thereby making the device slow in action, because of the introduction in the circuit of an extra highly inductive element, such as the winding or windings of the magnet of the single vibrator. In my invention I utilize an 30 induction coil for each cylinder of the engine, and in circuit therewith I utilize a single vibrator device having my improved double wound magnet, wherein a plurality of cores each having a winding, which windings are 35 substantially equal in number of turns and of substantially the same gage of wire, and said windings are wound in opposite directions and are connected in multiple with respect to each other, and each such winding is in series in the circuit with the corresponding induction coils of the engine, whereby the current traversing the circuit at any time splits or divides at said windings of the vibrator magnet and thereby reduces inductance in 45 said vibrator windings. Such magnet operates the vibrator to make and break the circuit of the primaries of the induction coils. In order to reduce any self induction in the magnet coils due to the make and break of 50 the armature circuit by the armature or vibrator, I provide a relatively small condenser bridged across between the windings or the terminals of the windings of the vibrator magnet. A condenser may also be used

bridged across the make and break contacts 55 of the vibrator in the usual manner.

In the accompanying drawings I have diagrammatically illustrated my invention in connection with a six cylinder gas engine provided with ordinary spark plugs of the 60 jump spark variety.

The engine is indicated generally at A and the spark plugs at B, one terminal of each plug being, as usual, grounded at the engine and the other terminal in circuit with the 65 corresponding secondaries C of the induction coils D, by means of conductors C', the opposite terminals of which secondaries are grounded through the engine, as represented at E. The primaries F of the induction coils 70 are connected, as by conductors f, with the respective terminals 1, 2, 3, 4, 5, 6 of a suitable timer, whose contact or arm 7 may be driven by the engine in usual manner, and is in electrical connection with the engine, as 75 through conductor 8. The opposite terminals of the primaries, as 1^a, 2^a, 3^a, 4^a, 5^a, 6^a, are connected as by wire 9 with the vibrator or vibrating spring 10 having a contact point 11 adapted for engagement with a 80 contact 12 shown carried by an adjusting screw 13 fitted to a bridge or support 14 in any well known manner. The armature 10^a of the vibrator 10 is shown of sufficient area 85 to co-act with the cores 15, 15^a of an electro magnet having two windings 16, 16^a, one winding upon each of said cores, which windings are connected at their corresponding terminals a, b, and said windings are wound 90 in opposite directions, and are of substantially the same number of turns and the same gage wire. The conductor 9^a connects with corresponding ends a of said windings and the conductor 9^b connects with the opposite corresponding ends b of said windings 95 and is grounded at the engine, and such circuit includes a battery 17 or any other suitable source of electrical energy. I have shown the cores 15, 15^a substantially in the form of a horseshoe or U-shape, whereby the 100 two cores are connected together at corresponding ends. The arrangement of said windings is such that the current will split or divide at the windings, passing substantially one half through each winding, and thereby 105 a north pole is produced at the end of one core and a south pole is produced at the corresponding end of another core, whereby the

passage of the current through the oppositely wound windings substantially reduces inductance and materially reduces resistance, and thus the current suffers very little impedance in its passage to the primaries F of the induction coils.

To reduce any self induction in the coils or windings 16, 16^a, due to the make and break of the magnet circuit by the armature 10^a or 10, vibrator 10 I provide a suitable or relatively small condenser 18 which is bridged across the corresponding terminals of the windings 16, 16^a, as by being in circuit with the terminals a, b, as shown by the wires 18^a, 18^b, 15 connecting with conductors 9^a, 9^b. A suitable condenser 19 may be bridged across the contacts 11 and 12 in any well known manner, being shown connected with conductor 9^a at 19^a and with the vibrator 10 20 at 19^b.

By means of my improvements all of the primary induction coils will operate accurately with respect to the time of the closing of the corresponding circuit at the commutator or timer, and material retardation by the vibrating mechanism is prevented because of the greatly reduced inductance and resistance at the vibrator windings.

Having now described my invention what 30 I claim is:

1. The combination of a plurality of induction coils with a vibrator provided with a plurality of windings having corresponding terminals permanently connected together 35 to reduce inductance, and said terminals connected to opposite sides of the circuit of the primaries of the induction coils.

2. The combination of a plurality of induction coils with a vibrator provided with a 40 plurality of windings having corresponding terminals connected together, said terminals connected to opposite sides of the circuit of the primaries of the induction coils, and a condenser connected with opposite terminals 45 of said windings.

3. The combination of a plurality of induction coils with a vibrator provided with a 50 plurality of windings wound in opposite directions and having corresponding terminals permanently connected together and said terminals connected with opposite sides 55 of the circuit of the primaries of the induction coils.

4. The combination of a plurality of induction coils with a vibrator provided with a 60 plurality of windings wound in opposite directions and having corresponding terminals connected together, said terminals connected with opposite sides of the circuit 65 of the primaries of the induction coils, and a condenser connected with opposite terminals of said windings.

5. The combination of a plurality of induction coils with a vibrator device having a 70 plurality of cores and a plurality of windings

on said cores, the corresponding terminals of said windings being permanently connected together and connected with opposite sides of the circuits of the primaries of the induction coils.

6. The combination of a plurality of induction coils with a vibrator device having a plurality of cores and windings on said cores, the corresponding terminals of said windings being connected together and connected 75 with opposite sides of the circuit of the primaries of the induction coils, and a condenser bridged across opposite terminals of said windings.

7. The combination of a plurality of induction coils with a vibrator device comprising a plurality of cores each having a winding, said windings being wound in opposite directions, and corresponding terminals 80 permanently connected together and connected to opposite sides of the circuit of the primaries of the induction coils.

8. The combination of a plurality of induction coils with a vibrator device comprising a plurality of cores each having a 85 winding, said windings being wound in opposite directions, and corresponding terminals connected together and connected to opposite 90 sides of the circuit of the primaries of the induction coils, and a condenser bridged across 95 opposite terminals of said windings.

9. An electrical ignition apparatus comprising a plurality of induction coils, a vibrator device provided with a plurality of windings of the same size wire connected in multiple with the circuit of the primaries of the 100 induction coils, a source of electrical energy included in the circuit of said windings and coils, and a timer for the primary circuits of said coils.

10. An electrical ignition apparatus comprising a plurality of induction coils, a vibrator device provided with a plurality of windings connected in multiple with the circuit of the primaries of the induction coils, a 110 source of electrical energy included in the circuits of said windings and coils, a timer for the primary circuits of said coils, and a condenser bridged across the corresponding terminals of said windings.

11. An electrical ignition apparatus comprising a plurality of induction coils, a vibrator device in circuit with said coils and provided with a plurality of windings wound in opposite directions and corresponding terminals of said windings permanently connected with the same side of the circuit of the primaries of the induction coils, the opposite terminals of said windings being permanently connected together, a source of 120 electrical energy included in the circuit of said primaries and said windings, and a timer for the primaries of the induction coils.

12. An electrical ignition apparatus com- 130

prising a plurality of induction coils, a vibrator device in circuit with said coils and provided with a plurality of windings wound in opposite directions and corresponding terminals of said windings connected with the same side of the circuit of the primaries of the induction coils, a source of electrical energy included in the circuit of said primaries and said windings, a timer for the primaries of the induction coils, and a condenser bridged across the corresponding terminals of the vibrator windings. 5

13. An electrical ignition apparatus, comprising a plurality of induction coils, a vibrator device provided with a plurality of cores, a winding on each core, corresponding terminals of said windings being permanently connected together and also connected with corresponding sides of the circuit of the primaries of the induction coils, a source of electrical energy included in the circuits of said primaries and said vibrator windings and a timer for said primary circuits. 10

14. An electrical ignition apparatus, comprising a plurality of induction coils, a vibrator device provided with a plurality of cores, a winding on each core, corresponding terminals of said windings being connected together and also connected with corresponding sides of the circuit of the primaries of the induction coils, a source of electrical energy included in the circuits of said primaries and said vibrator windings, a timer for said primary circuits, and a condenser bridged across opposite terminals of the vibrator windings. 20

15. An electrical ignition apparatus comprising a plurality of induction coils, a vibrator device in circuit with the primaries of said coils and having a plurality of cores provided with windings wound in opposite directions, corresponding terminals of said windings being permanently connected together and also connected with opposite sides of the circuit, a source of electrical energy included in the circuit of said primaries and said vibrator windings, and a timer for the primaries of said induction coils. 30

16. An electrical ignition apparatus comprising a plurality of induction coils, a vibra-

tor device in circuit with the primaries of said coils and having a plurality of cores provided with windings wound in opposite directions, corresponding terminals of said windings being connected together and also connected with opposite sides of the circuit, a source of electrical energy included in the circuit of said primaries and said vibrator windings, a timer for the primaries of said induction coils and a condenser bridged across opposite terminals of said vibrator windings. 50

17. An electrical vibrator comprising a plurality of cores, and a plurality of windings on said cores, the corresponding terminals of said windings being permanently connected together, an armature for said cores, and make and break contacts controlled by said armature. 55

18. An electrical vibrator comprising a plurality of cores, and a plurality of windings on said cores, the corresponding terminals of said windings being connected together, an armature for said cores, make and break contacts controlled by said armature, and a condenser bridged across opposite terminals 70 of said windings. 75

19. An electrical vibrator comprising a plurality of cores each having a winding, said windings being wound in opposite directions and corresponding terminals permanently connected together, an armature for said cores, and make and break contacts controlled by said armature. 80

20. An electrical vibrator comprising a plurality of cores each having a winding, said windings being wound in opposite directions and corresponding terminals connected together, an armature for said cores, make and break contacts controlled by said armature, and a condenser bridged across opposite terminals of said windings. 85 90

Signed at New York city, in the county of New York and State of New York this 21st day of January, A. D. 1908.

THEODORE HUBERT.
